UNITED STATES PATENT OFFICE.

TOBIAS F. KELLER, OF PHILADELPHIA, PENNSYLVANIA, ASSIGNOR TO
EUGENE IVINS, OF SAME PLACE.

DESIGN FOR A BISCUIT.

SPECIFICATION forming part of Design No. 24,364, dated June 4, 1895.

Application filed March 13, 1895. Serial No. 541,629. Term of patent 3½ years.

To all whom it may concern:

Be it known that I, TOBIAS F. KELLER, a citizen of the United States, residing at the city of Philadelphia, in the county of Philadelphia and State of Pennsylvania, have invented and produced a certain new and original Design for a Biscuit or Similar Article, of which the following is a specification.

The leading feature of my design consists of a biscuit or similar article in the shape or form of a crescent with a face in profile disclosed in connection with or forming part of the crescent.

In the accompanying drawings, Figure 1 is a perspective view of a biscuit embodying the features of shape or form and ornamentation of my design; and Fig. 2 is an end view looking toward the right of Fig. 1, showing the surface ornamentations thereof.

Referring to the drawings A, is a crescent having a curved outline body in part and having projecting points or horns a and a' , at the upper and lower portions of the body and as

a continuation the surface ornamentation b , representing an eye, the surface ornamentation b' , outlining a brow, the surface ornamentation b^2 , beneath the eye, the outline ornamentation b^3 , the line ornamentations b^4 and b^5 , about and to define a nostril, the line ornamentation b^6 , to outline and define a mouth and the line ornamentation b^8 , to outline a chin.

What I claim as new, and desire to secure by Letters Patent, is—

The design for a biscuit or similar article having the raised surface ornamentations falling within an irregular crescent-shaped outline and adjacent to the profile edge of the biscuit, as illustrated and described.

In testimony whereof I have hereunto set my signature in the presence of two subscribing witnesses.

TOBIAS F. KELLER.
